CONTROL PANEL FOR A FABRIC TREATING MACHINE

Dudley P. Combs, Newton, Iowa, assignor to The Maytag Company, Newton, Iowa, a corporation of Delaware

Application May 12, 1954, Serial No. 30,424

Term of patent 14 years

(Cl. D49—1)

FIG. 1

FIG. 2

FIG. 3

FIG. 4

FIG. 5

To all whom it may concern:

Be it known, that I, Dudley P. Combs, a citizen of the United States, residing at Newton, county of Jasper, and State of Iowa, have invented a new, original, and ornamental Design for a Control Panel for a Fabric Treating Machine, of which the following is a specification, reference being had to the accompanying drawing, forming a part thereof.

Figure 1 is a view in front elevation of a control panel for a fabric treating machine embodying my new design.

Figure 2 is a front perspective view thereof.

Figure 3 is a phantom outline taken on line 3—3 of Figure 1.

Figure 4 is a similar view taken on line 4—4 of Figure 1.

Figure 5 is a similar view taken on line 5—5 of Figure 1.

I claim:

The ornamental design for a control panel for a fabric treating machine substantially as shown.
